US0D1077636S

(12) **United States Design Patent** (10) Patent No.: **US D1,077,636 S**
(45) Date of Patent: ** Jun. 3, 2025

(54) **BEVERAGE BOTTLE**

(71) Applicant: **HARIO Co., Ltd.**, Tokyo (JP)

(72) Inventor: **Atsuko Sakamoto**, Tokyo (JP)

(73) Assignee: **Hario Co., Ltd.**, Tokyo (JP)

(**) Term: **15 Years**

(21) Appl. No.: **35/520,714**

(22) Filed: **Feb. 2, 2024**

(80) **Hague Agreement Data**

Int. Filing Date: **Feb. 2, 2024**

Int. Reg. No.: **DM/236262**

Int. Reg. Date: **Feb. 2, 2024**

Int. Reg. Pub. Date: **May 3, 2024**

(30) **Foreign Application Priority Data**

Nov. 20, 2023 (JP) ..... 2023-023940 D

(51) **LOC (15) Cl.** **09-07**

(52) **U.S. Cl.**

USPC **D9/504**; D9/558; D9/719

(58) **Field of Classification Search**

USPC D9/500–504, 516, 522, 529, 542–545, D9/549–550, 558, 563, 571–575, 652, D9/682, 686, 687–688, 690, 715, 719; D3/201, 202, 316; D7/509–511, 300, D7/302–303, 316; D24/107, 121–123, D24/216, 217, 224

CPC ... B65D 1/00; B65D 1/02; B65D 1/12; B65D 1/18; B65D 1/20; B65D 1/0223; B65D 23/00; B65D 21/0237; B65D 2501/009; B65D 2501/0081; B65D 2543/00296; B65D 2543/00092; B65D 41/26; B65D 2501/00; B65D 2501/0009
